UNITED STATES PATENT OFFICE.

SIMON A. JAROSLAWSKI-FIORET, OF NEW YORK, N. Y., ASSIGNOR TO FIORET, INC., OF NEW YORK, N. Y., A CORPORATION OF NEW YORK.

DESIGN FOR A VANITY CASE.

Application filed October 23, 1924. Serial No. 11,162. Term of patent 14 years.

To all whom it may concern:

Be it known that I, SIMON A. JAROSLAWSKI-FIORET, a citizen of Poland, and a resident of the city of New York, borough of Manhattan, in the county of New York and State of New York, United States of America, have invented a new, original, and ornamental Design for a Vanity Case, of which the following is a specification.

Reference is had to the accompanying drawing in which—

I claim:

The ornamental design for a vanity case as shown.

SIMON A. JAROSLAWSKI-FIORET.
